UNITED STATES PATENT OFFICE.

ERNEST H. J. LORENZ, OF MADISON, WISCONSIN, ASSIGNOR TO CHARLES F. BURGESS,
OF MADISON, WISCONSIN.

CUTTING-OFF MACHINE.

1,006,574.

Specification of Letters Patent. Patented Oct. 24, 1911.

Application filed December 3, 1910. Serial No. 595,354.

To all whom it may concern:

Be it known that I, ERNEST H. J. LORENZ, a citizen of the United States, residing at Madison, county of Dane, State of Wisconsin, have invented certain new and useful Improvements in Cutting-Off Machines, of which the following is a specification.

The main objects of the present invention are to provide means whereby the lining of a can or similar receptacle or article of manufacture may be trimmed or cut away to leave a smooth edge located at a pre-determined distance from the top or end of the can; to provide cutting means operative on a wet paper lining; to provide mechanism for preventing injury to the receptacle, even when the receptacle consists of soft material such as zinc; to provide means for automatically turning or moving the material under treatment during the cutting operation, and in such a way that the speed of movement is governed by the rapidity with which the cutter passes through the material to be cut or trimmed; to provide various details of structure and a special arrangement of parts whereby the cutting-off or trimming operation can be effectively applied to cut away the superfluous stock of a wet paper lining within a zinc can of a kind suitable as one electrode of a dry battery.

In the drawings forming a part of this specification, Figure 1 is an elevation of the cutting-off machine with certain of the elements broken away, showing in section, the zinc container of a primary battery with its paper lining; Fig. 2 is an end elevation of the same with the zinc container removed.

In the construction shown, the apparatus comprises a vertical standard having a cylindrical portion 1 and a rectangular portion 2. Adjustably mounted on the cylindrical portion of this standard is an arm or bracket 3, carrying at its outer end a socket within which is a vertical shaft 4, free to turn or rotate and carrying at its top a support or platform 5 on which the work to be trimmed or cut can be seated. The upper end of the rectangular portion 2 of the vertical standard is anchored or supported by a wall-bracket 6. Below this bracket are two arms 7 and 8, secured rigidly to either side of the standard 2 and carrying at their outer ends a pivot 9 on which is mounted a swinging cutter-head 10. The cutter-head can be swung outward about the pivot 9 to facilitate introduction or removal of the material to be cut off.

As a means for swinging the cutter-head, there are provided a pair of links 11 and 12, secured to the cutter-head by a pivot 13 and 60 having at their inner ends a pivotal connection 14 with a bell crank lever 15. This lever has a lower arm 16, provided with a set screw 17 to serve as a stop for limiting the inward movement of the cutter-head. 65 Secured to the inner end of the bell crank lever 15 is a manually operative rod 18, carrying on its upper end a stop 19, forming an abutment for a rubber cushion 20. This cushion limits the amount of power which 70 can be applied to the lever 15 when the rod 18 is depressed.

Within the cutter-head 10 is a rotary shaft 21, carrying at its lower end a beveled annular cutter 22. This shaft 21 is connected through universal couplings 23 and 24 and a telescoping rectangular drive shaft 25 with a driving pulley 26, over which passes a driving band 27. The rotary cutter, therefore, is driven in a positive manner and at a pre-determined and suitable speed.

The material to be operated upon is shown in the drawings as consisting of a zinc can 28, of a kind suitable as the container for a dry battery. This can has a recessed bottom fitting over the platform 5 of the rotary support. Within this can is the usual heavy paper lining 29, which lies directly in contact with the zinc and ordinarily is wet or 90 damp when the cutting-off or trimming operation is to be effected. Bearing against the outer surface of the can, just opposite its point of contact with the cutter 22, is a rotary block 30 of rubber or similar yielding material, carried on a pivot 31, which is mounted in a bracket 32, bolted to the side of the rectangular standard 2. This rubber roller affords a yielding seat against which the soft zinc can be pushed by the rotary 100 cutter. Its yielding character allows the cutter to run in direct contact with the zinc, but without danger of cutting into the zinc to a detrimental extent. Two guide arms 33 and 34 may be mounted at the side of the 105 standard 2 to limit and to guide the movements of the can.

In normal operation, the manually operative rod 18 is raised, allowing the cutter-head to swing outward and upward about 110

its pivotal support 9. A zinc can with its paper lining is then slipped into place on the platform 5 and the rod 18 depressed to bring the positively driven cutter 22 into contact with the paper lining 29. The cutter goes through the paper into contact with the zinc and its friction on the zinc serves to turn the can support 5 at just the proper speed to insure most efficient action of the rotary cutter. If the paper happens to be unusually tough or thick, or the cutter happens to be dull from repeated use, the machine automatically adjusts itself to these unusual conditions and feeds the paper to the cutter no faster than the cutter can do its work properly.

Although I have herein described an embodiment of my invention well adapted for trimming the paper linings of a dry battery, its usefulness in other relations will be apparent to those skilled in the art.

What I claim as new and desire to secure by Letters Patent of the United States is:—

1. In a cutting-off machine for receptacle linings, the combination of a positively driven cutter, and means for supporting the work to be cut in position to be moved solely by the friction of said cutter thereon.

2. In a cutting-off machine for receptacle linings, the combination of a positively driven cutter, and a rotary support for the work to be cut, said support being arranged for rotation by the friction of said cutter on said work.

3. In a cutting-off machine, the combination of a rotary cutter, means for driving said cutter at a definite speed, and a support for the work to be cut, said support being arranged to allow free rotation of said work under the driving action of said cutter.

4. In a cutting-off machine, the combination of an annular and positively driven rotary cutter, and means for yieldingly holding material to be cut in engagement with said cutter, said holding means admitting of rotary movement of said material under the driving impulse of said rotary cutter.

5. In a cutting-off machine for can coverings, the combination of a beveled rotary cutter adapted to frictionally engage the can and thereby move the same, means for positively rotating said cutter, and a yielding block opposed to said cutter and protecting said can from a deep incision by said cutter.

6. In a cutting-off machine, the combination of a rotary cutter adapted to frictionally engage the work and thereby move the same, means for positively rotating said cutter, a yielding roller bearing on said work opposite said cutter, and a rotary support for said work allowing free rotation thereof under the driving action of said cutter.

7. In a cutting-off machine, the combination of a positively driven rotary cutter, a yielding rotary block for holding material

against said cutter, and means for supporting the work to be cut in position to be moved solely by the friction of said cutter thereon.

8. In a cutting-off machine, the combination of a pivoted cutter head, a rotary cutter carried by said head, means for positively driving said cutter, manually operative means for swinging said cutter-head to bring said cutter into engagement with the work to be cut, and a yielding roller for holding said work against said cutter. 70 75

9. In a cutting-off machine, the combination of a pivoted cutter-head, a rotary cutter carried by said head, means for positively driving said cutter, a yielding roller opposite said cutter, means for swinging said cutter into cutting position near said roller, and a rotary support for holding material between said cutter and said roller, said support allowing free rotary movement of said material under the driving action of said cutter. 80 85

10. In a cutting-off machine, the combination of a standard, a cutter-head pivotally supported therefrom, a rotary cutter journaled in said cutter-head, a rotary support for holding material to be cut in position near said cutter, manually operative means for swinging said cutter against said material to be cut, said means having a yielding connection with said cutter to prevent undue pressure of said cutter against said material, and a yielding roller opposite said cutter. 90 95

11. In a cutting-off machine, the combination of a standard, a bracket slidingly mounted thereon, a rotary can support carried by said bracket, a cutter-head pivotally supported from said standard, a rotary cutter journaled in said head, means for positively driving said cutter, a yielding roller supported opposite said cutter, and manually operative means for yieldingly holding said cutter adjacent said roller, to cut away 100 105 material passing between said cutter and said roller.

12. In a cutting-off machine for battery receptacles, the combination of a standard, a rotary support carried by said standard and adjustable thereon, a cutter-head pivotally mounted on said standard, a beveled rotary cutter journaled to said cutter-head, universal couplings connected to said cutter, means for driving said cutter through said couplings, and manually operative means for moving said cutter-head on its pivotal mounting, said last-named means having a yielding connection with said cutter-head to prevent undue pressure on said cutter during the cutting operation. 115 120

13. In a cutting-off machine for receptacle linings, the combination of a rotary cutter, means for driving said cutter, a rotary support for the work to be cut, said support be- 125 130

ing arranged for rotation solely by the friction of said cutter on said work, and means for moving said cutter into and out of engagement with said work.

14. In a cutting-off machine, the combination of a pivoted cutter head, a rotary cutter carried by said head, means for positively driving said cutter, means for swinging said cutter head to bring said cutter into engagement with the work to be cut, and a yielding roller for holding said work against said cutter.
- 10 15. In a cutting-off machine, the combination of a pivoted cutter head, a rotary cut-

ter carried by said head, means for positively driving said cutter, means for swinging said cutter into cutting position, and a rotary support for holding material in position to be cut, said support allowing free rotary movement of said material under the driving action of said cutter.

In witness whereof, I hereunto subscribe my name this 26th day of November, 1910.

ERNEST H. J. LORENZ.
